UNITED STATES PATENT OFFICE.

JAMES A. MACDONALD, OF BOSTON, MASSACHUSETTS.

SINEW EXTRACTOR.

Application filed July 28, 1926. Serial No. 125,413.

This invention relates to a sinew extractor of the type shown by the Congdon Patent, No. 941,759, dated November 30, 1909, said extractor consisting of a base adapted to be attached in a vertical position to a fixed upright support, a forwardly extending foot-holder fixed to the base and having a forked end portion, a hand lever connected at its inner end with the base by a pivot located below and at one side of the foot-holder, the lever being movable in a vertical plane, and a leg-engaging member or claw including jaws extended laterally from the lever at a point intermediate the length of the lever on the side adjacent to the foot-holder, the jaws being adapted to engage an enlarged fleshy portion of a fowl's leg below the foot-holder when the lever is raised, and operating to separate the leg from the foot and extract the sinews when the lever is moved downward, all as more particularly set forth by the Congdon patent.

The present invention is an improvement on the device of the Congdon patent, and is embodied in a foot-holder formed to engage the bony portions of legs of different sizes, and a multiple claw on the lever, also formed to engage the bony portions of legs of different sizes, so that the extractor may operate on larger or smaller legs, without adjustment of any of its parts, and without liability of the wedging adhesion of a broken off foot and leg portion to the arm.

Of the accompanying drawings forming a part of this specification,—

Figure 1 is a front elevation of a sinew extractor embodying my improvement, the lever being fully lowered.

Figure 2 is a side elevation of the same.

Figure 3 is a side elevation, showing the lever raised, and the foot holder and two of the prongs engaged with a larger leg, the sinews being partly extracted.

Figure 4 is a view similar to Figure 3, showing the foot-holder and two of the prongs engaged with a smaller leg.

The same reference characters indicate the same parts in all of the figures.

a designates a base adapted to be secured to a wall by screws or otherwise. *b* designates a foot-holder which is an arm or bracket projecting forward from the base and having a bifurcated or recessed outer end. The space or recess between the fingers of the forked end is made wide enough to receive the bony part of the leg, as shown

by Figures 3 and 4, and the adjacent edges of said recess are beveled and provided with a sharp edge on the upper side of the lower finger over which the leg may be easily broken, as shown by the Congdon patent.

c' designates the hand lever connected by a pivot *c*², to ears on the base, the pivotal connection being arranged as heretofore, below and at one side of the foot-holder.

The leg-engaging member in the Congdon patent is a claw, arranged on and rigidly attached to the lever *c*' near its pivot, and projects laterally from that side of the lever adjacent the foot-holder, so that when the lever is fully raised on its pivot, the claw engages the leg below the foot-holder, and then, as the lever is moved downward, the fleshy part of the leg is drawn down, while the bony part remains fixed in the foot-holder, so that the sinews are extracted from the fleshy part of the leg, as described by the Congdon patent.

In carrying out the present invention, I provide the foot-holder recess with a wider outer portion, formed by parallel recess edges 12, 12 constituting outer jaws, spaced apart to receive between them the bony portion *d* of a larger leg adjoining the foot *e*, as shown by Figure 3, and a narrower inner portion, formed by parallel recess edges 13, 13 constituting inner jaws, spaced apart to receive between them the bony portion of a smaller leg, as shown by Figure 4. The leg shown by Figure 3, may be that of a turkey, and the leg shown by Figure 4, that of a hen.

I also provide the lever *c* with a multiple claw, composed of two end prongs 14 and 15, and an intermediate prong 16. The end prong 14 is spaced from the intermediate prong 16, by a recess, the edges of which constitute outer jaws adapted to engage the bony portion *d* of a larger leg adjoining the fleshy portion *f*, as shown by Figure 3, while the end prong 15 is spaced from the intermediate prong by a recess, the edges of which constitute inner jaws adapted to engage the bony portion of a smaller leg, as shown by Figure 4. The operator, may, therefore, use the outer jaws of the arm *b* and the outer jaws formed by the claws 14 and 16 on a relatively large leg, and the inner jaws of the arm and the inner jaws formed by the claws 15 and 16 on a smaller leg.

The parallelism of the outer and inner arm

jaws formed by the edges 12, 12 and 13, 13, is important, because the said jaws are thereby adapted to have a non-wedging engagement with the body portion adjoining the foot, so that the broken-off leg portion adhering to the foot is not liable to have a wedging adhesion to the arm, and drops freely from the arm after the sinew-extracting operation. If the edges of the arm recess were inclined relative to each other, to form a wedge-shaped recess, the broken off leg portion adjoining the foot would be liable to adhere to the arm and require forcible pulling out by the operator, so that loss of time would be involved.

I claim:

A sinew extractor including a base, a foot-holding arm projecting forward from the upper portion of the base and having a recess adapted to receive the bony portion of a fowl's leg adjoining the foot, said recess being composed of a relatively wide parallel sided outer portion, the edges of which form

outer jaws adapted to have a non-wedging engagement with a larger leg, and a narrower parallel sided inner portion, the edges of which form inner jaws adapted to have a non-wedging engagement with a smaller leg, and a hand lever pivoted to the base below the arm, and provided with a multiple claw adapted to receive the bony portion of a leg adjoining the fleshy portion thereof, said claw having a larger recess, the edges of which form outer jaws, formed and positioned to cooperate with the outer jaws of the arm in extracting sinews from a larger leg, and a smaller recess, the edges of which form inner jaws, formed and positioned to cooperate with the inner jaws of the arm in extracting sinews from a smaller leg, the parallelism of the arm jaws preventing a wedging adhesion of a broken off leg and foot to the arm.

In testimony whereof I have affixed my signature.

JAMES A. MACDONALD.
